UNITED STATES PATENT OFFICE.

HIRAM STEVENS MAXIM, OF STREATHAM, LONDON, ENGLAND, ASSIGNOR TO VICKERS
LIMITED, OF WESTMINSTER, ENGLAND.

FLYING-MACHINE BOMB.

1,077,991.

Specification of Letters Patent. Patented Nov. 11, 1913.

Original application filed March 25, 1912, Serial No. 686,002. Divided and this application filed February 18, 1913. Serial No. 749,289.

To all whom it may concern:

Be it known that I, HIRAM STEVENS MAXIM, a subject of the King of Great Britain, residing at "Sandhurst Lodge," 5 382 High road, Streatham, in the county of London, England, formerly of "Ryecotes," Dulwich Common, in the county of London aforesaid, have invented certain new and useful Improvements in or Relating 10 to Flying-Machine Bombs, of which the following is a specification.

This invention relates to bombs for use with aeroplanes and other flying machines or balloons of the character described in 15 the specification of my co-pending application for Letters Patent Serial No. 686,002 filed March 25, 1912, and of which this application is a division, in which a detonating charge is retained in a position remote 20 from the main charge until the bomb is discharged or released and in which the bomb is adapted to be exploded at a predetermined distance above or from the ground, object or target, by the initial impact of 25 a "pilot" device adapted to precede the bomb in its travel toward the target so that the firing of the main charge may be brought about when the bomb is in the most favorable position for performing effective 30 work.

According to this invention the aforesaid "pilot" device is in connection or communication with the detonating charge by means of a fuse which may be of the instantaneous or other suitable type and is adapted to fire the fuse on impact with the ground, object or target. The fuse may be so arranged that the continuity thereof is interrupted until the bomb is released.

The shell or casing of the bomb may, in the usual manner, be formed or provided with grooves with or without a loading of metal fragments or balls or the like having the interstices between the same filled with a high explosive so that destructive fragments or bodies are disseminated or spread by the explosion, the effect of the latter being thus productive of the desired destruction, in regard both to life and buildings or erections. The height at which the

explosion of the main charge will take place will depend upon the length of the connection between the bomb and the "pilot."

In order that the said invention may be clearly understood and readily carried into effect I will proceed to describe the same with reference to the accompanying drawings in which:—

Figure 1 is an elevation showing the improved bomb attached to the aeroplane or flying machine. Fig. 2 is a partial sectional view of said bomb. Fig. 3 is a sectional view of the tubular extension thereon showing the detonating charge and parachute. Fig. 4 is an end view of the tubular extension. Fig. 5 is a diagrammatic view showing the position of the bomb when explosion takes place. Fig. 6 is a detail view of the firing pin and means for securing the same in the inoperative position.

Referring to Figs. 1 to 5, the bomb comprises a shell or casing α which is provided with an internal hollow member α^2 which extends beyond said casing to form a tail piece α^3 and said tail piece is provided with a number of hinged members α^4 which, when the bomb is released, are adapted to extend in the same manner as an umbrella to constitute a parachute. If desired a suitable fabric or the like may be arranged on or spread over the said members. The members α^4 are hinged to the tail piece α^3 at α^5 and are retained in the closed position by a band α^6 carried by the machine. One or more of the members α^4 may be provided with an extension α^7 which is adapted to enter a corresponding opening or aperture α^8 formed in the tail piece α^3 of the bomb. The extension α^7 enters the opening α^8 when the parachute is in the closed position, and serves to retain an auxiliary or detonating charge α^9 at the extremity of the tail piece remote from the main charge of picric acid or other high explosive contained in the space between the shell α and the internal hollow member α^2 . When the members α^4 are extended the auxiliary or detonating charge is free to move toward the main charge into the firing position. The bomb is secured

to the framing b of the aeroplane or flying machine by means of a rod or bolt b' which is adapted to engage with openings b^2 formed in lugs b^3 carried by the shell of the 5 bomb. The bomb rests in saddle pieces b^4 on the framing b and by operating the lever or handle b^6 the rod b' may be released from the lugs b^3 and the bomb liberated. Said lever b^5 is also adapted to operate another rod b^6 so as to release the band a^6 which normally retains the members a^4 of the parachute in the inoperative position.

d is a fuse which may be of the type commonly known as instantaneous or very quick 15 action. One end of the fuse d is secured in or to the bomb while the other end is connected with a "pilot" d' which is detachably mounted on the forward extremity of the bomb. Two depending pins or arms d^x , 20 d^2 are provided on the framing of the machine and serve respectively to retain the "pilot" d' upon the bomb and to dam or cut off communication between the portions of the fuse in the "pilot" and in the bomb, 25 and to retain the firing pin d^8 in the inoperative position. Thus in the event of the fuse d exterior of the bomb being accidentally fired the fuse situated inside the bomb will not be affected thereby. The 30 "pilot" d' is provided with the firing pin d^8 adapted to project from its forward end or any other suitable part, the inner end being adapted to strike a primer or cartridge d^4 which then fires the fuse. The 35 fuse d is formed in two lengths d^7 , d^8 secured together by a suitable coupling piece d^9 and is continued to the rear end of the bomb through which rear end it passes to the detonating charge a^9 in the tubular tail 40 piece a^3 of the bomb. The depending pin or arm d^x enters the forward end d^5 of the bomb and passes through an opening in the coupling piece d^9 in such a manner as to break the continuity of the fuse d excepting 45 when the said pin or arm is withdrawn upon the release of the bomb from the machine. The arrangement, may, however, be such that the fuse exterior to the bomb is not in alignment with that in the interior of the 50 bomb; the releasing of the bomb from the machine having the effect of bringing the parts of the fuse into line for effective action. The fuse d is coiled up so as to be capable of stowage in the "pilot" d' of the 55 bomb, the construction of which is arranged in such a manner as to admit of such stowage. When the bomb is released from the machine the detonating charge a^9 and the pilot d' will gravitate to their extreme forward 60 positions and so soon as the pilot reaches the object or target as shown in Fig. 5 the bomb will be exploded in the manner described. A buffer is provided for cushioning the detonating charge a^9 at the 65 end of its forward movement and said buffer

may comprise a number of rubber rings d^{10} arranged within the tubular chamber a^2 of the bomb. The firing pin d^3 pertaining to the pilot is impelled against the primer d^4 by means of the springs d^6 which are normally inclined to the vertical axis in such manner as to retain the firing pin in the forward position remote from the primer. When the extremity of the firing pin strikes the ground or target, the pin is pushed back against the action of said springs d^6 until it passes the neutral position, that is, when the axis of the springs d^6 are in the vertical position. Further movement of the pin will cause the springs to be displaced from this neutral position in the opposite direction and the tendency is for them to suddenly spring out and carry the pin against the primer. In this way, the springs d^6 serve normally to retain the pin in the inoperative position, and after the initial displacement of the pin they serve to impel the same against the primer. If desired, the pin d^3 may be retained by a pin or the like d^{11} (Fig. 6) which is adapted to be sheared 90 when the bomb strikes the object or target.

What I claim and desire to secure by Letters Patent of the United States is:—

1. In a bomb for use with aeroplanes or flying machines the combination of a main charge of high explosive, a detonating charge capable of moving relatively to the main charge into the operative position during the descent of the bomb, a parachute for retarding the motion of the bomb during its descent, a pilot device adapted to precede the bomb and an instantaneous or quick action fuse leading from said pilot device to the detonating charge.

2. In a bomb for use with aeroplanes and flying machines the combination of a main charge of high explosive, a detonating charge capable of moving relatively to the main charge, a parachute for retarding the motion of the bomb during its descent, a pilot device adapted to precede the bomb, an instantaneous or quick action fuse connected to the detonating charge and a firing means carried by said pilot device and adapted to ignite said fuse so as to explode 115 the detonating and main charges.

3. In a bomb for use with aeroplanes or flying machines the combination of a main charge of high explosive, a detonating charge capable of moving relatively to the main charge, a parachute for retarding the motion of the bomb during its descent, a firing device which when the bomb is released assumes a position in advance thereof and an instantaneous or quick action fuse 120 extending between the detonating charge and the firing device and the continuity of which is interrupted until the bomb is released.

4. In a bomb for use with aeroplanes or 125

flying machines the combination of a main charge of high explosive, a detonating charge capable of moving relatively to the main charge, a parachute for retarding the motion of the bomb during its descent, a pilot device provided with a spring controlled firing pin, a bi-part instantaneous or quick action fuse extending between the detonating charge and the pilot device, a cou-

pling for the two parts of said fuse and means for breaking the continuity of the fuse until the bomb is released.

In testimony whereof I affix my signature in presence of two witnesses.

HIRAM STEVENS MAXIM.
